HOSIERY

Robert E. Davis, Fort Payne, Ala., assignor to W. B. Davis & Son, Inc., Fort Payne, Ala., a corporation of Alabama

Application July 24, 1943, Serial No. 496,041

3 Claims. (Cl. 66—182)

The invention relates to hosiery and more particularly to the toe thereof.

It is customary to knit so-called seamless socks on plain knitting machines having heel and toe mechanisms for reciprocating the knitting cylinder to form the heels and toes of the socks. While the heel and toe mechanism completely forms the heel of the sock, it is necessary to remove the sock from the knitting machine to complete the toe. It is customary to sew up the open edges of the toe by a separate machine known as a looper. This method of making socks is open to the objections that the sewing operation requires a complicated machine, skilled labor and is time consuming. These objections are multiplied when it is desired to place terry knit in the toe to make a cushion toe.

The present invention has for its object to form an improved toe by eliminating the toe looping operation and to substitute therefor a simple stitching operation capable of being performed by comparatively unskilled labor.

According to a preferred method of practising the invention, a seamless sock is made upon a tubular knitting machine having heel and toe mechanism, the top, leg portion, the heel and the foot portion being formed in a generally conventional manner. Instead of forming the toe by the heel and toe mechanism, the knitting machine continues to rotate, forming a succession of complete courses for a distance corresponding to the length of the toe. Incorporated with the thread at the beginning of the toe portion is an additional thread forming terry loops on the inside surface of the fabric. After forming the tubular, terry toe extension, the sock is removed from the knitting machine and pressed into flat position. The sock is then turned wrong side out and the flattened toe portion is cut to form tapered or rounded edges and the cut edges are stitched on an ordinary edging machine such as a Merrow sewing machine or seamer having sewing and binding threads. The seam projects on the inside of the sock when turned right side out.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with

the accompanying drawing forming a part hereof, in which

Fig. 1 is an outside view of the finished sock according to the invention after being boarded into flat position;

Fig. 2 is a view corresponding to Fig. 1 of the sock of Fig. 1 turned inside out;

Fig. 3 is a detail of the foot of the sock illustrating a stage in the manufacture of the complete sock;

Fig. 4 is an exaggerated view illustrating terry knit fabric;

Fig. 5 is a detail view, largely diagrammatic, showing a portion of the inside of the sock and illustrating the stitched seam according to the invention; and

Fig. 6 is a diagrammatic view taken on the line 6—6 of Fig. 5.

In the following description and in the claims, various details will be identified by specific names for convenience, but they are intended to be as generic in their application as the art will permit.

Like reference characters denote like parts in the several figures of the drawing.

In the drawing accompanying and forming part of this specification, certain specific disclosure of the invention is made for purposes of explanation, but it will be understood that the details may be modified in various respects without departure from the broad aspect of the invention.

Referring now to the drawing, the sock shown comprises a rib knit top 10, a plain knit leg portion 11, a plain knit heel pocket 12, a plain knit foot portion 13, and a terry knit toe portion 14 whose edges are connected by seam 15.

The top 10 is turned over and in and sewed to the leg portion by seam 9. Although the top 10 is shown to be a rib knit, turned down top, it is obvious that this top may be of any of the well known constructions, such as a mock rib top or an elastic top of the type shown in my Patent No. 2,306,246, dated December 22, 1942.

The leg portion 11 is preferably plain knit on a tubular knitting machine with the courses extending continuously around the tube in the usual manner. The foot portion 13 also comprises plain knit fabric with the courses extending all the way around the tube. The heel pocket 12 is of plain knit fabric with the courses extending partly around the tube as made by conventional heel and toe mechanism.

It will be understood that the top 10, leg portion 11, heel pocket 12, and foot portion 13 may be made in any suitable or desirable way as far as the line 32 which indicates the beginning of the

terry toe area. The hose may be of any desired length from a full length stocking to anklets.

Instead of using the heel and toe mechanism to form the toe 14, a tubular extension 28 will be knit onto foot portion 13 with the terry yarn added to form terry loops 19 on the inside of the tube. The terry yarn will be accompanied by a backing yarn in the conventional manner, the plain knit courses extending entirely around the tube for a sufficient length to form the toe, as will hereinafter more clearly appear.

The sock is then removed from the knitting machine, is turned wrong side out and pressed flat into the position corresponding to that of Fig. 2. The flattened tube is cut and stitched along the line indicated by 29 in Fig. 3 to form seam 15. Any stitching machine may be used but it is preferred to use a Merrow sewing machine or seamer which cuts the fabric as it seams. The sewing operation is performed with the sock turned inside out with the terry fabric exposed and the seam 15 is made using two threads 23 and 24.

The shape of the line 29 and corresponding seam may vary, depending upon the shape of the toe desired, and it may intersect the side edge of the tube at any desired distance from the margin 32 of the terry knit area, provided no cut edges are formed outside of the terry area. The seam may conveniently extend to a point 33 somewhat short of the margin 32 of the terry loop area.

The terry fabric cooperates with the stitched seam 15 in a novel and efficient way which will be more apparent from a consideration of Figs. 4 to 6. Figure 4 is an enlarged exaggerated view of a section of terry fabric including courses A, B and C and wales W, X, Y and Z. In this figure the backing yarn is denoted by 16 and the terry yarn by 17. The sinker loops of the backing yarn are denoted by 18 and the terry loops by 19. The needle loops of both the terry yarn and backing yarn are denoted by 20. It will thus be seen that the terry loops 18 form the well known characteristic pile. It will be seen that the line of cut 29 of the terry fabric extends both coursewise and walewise of the terry fabric. The seam 15 is formed by stitching the projecting edges or welts 27 of the toe flaps by a seam having an "outer" thread 23 and an "inner" or binding thread 24, the inner thread enclosing the loose cut edges of the welts 27 as illustrated diagrammatically in Figs. 5 and 6.

The threads 23 and 24 are stitched in the form of an edging stitch in which the loops 25 and 26 of the outer thread 23 pass through the fabric and across the outside of the sock and engage loops 30 and 31 of the inner thread 24 on the inner side of the sock, thus securely locking the seam against opening and binding in the cut edges or welts 27 to provide a neat appearing and soft seam 15.

After the seam 15 is completed, the sock is turned right side out and boarded and pressed flat in the usual manner to obtain a sock having the appearance of Fig. 1.

The present toe construction has many advantages over conventional toe constructions both as to the product itself and the method of making the product. The formation of an ordinary two-thread seam 25 on a Merrow sewing machine or seamer is a much simpler and quicker operation than connecting the free edges of a sock toe made with a conventional heel and toe mech-

anism by a looper, where the operator must line up the individual loops of the meeting edges and pass the threads of the seam through the end loops of the meeting edges. This operation, known as looping, requires not only a complicated machine, but skilled labor and is time consuming.

The terry fabric not only produces a cushion toe, but permits sewing by an ordinary sewing machine without causing unraveling or runs. The seam 15 is constructed without any regard to passing the seam threads through any particular loops of the fabric but the long pile of the terry fabric prevents runs notwithstanding. The two-thread seam encloses the cut edges of the fabric and the terry pile helps cushion this seam.

Furthermore, the seam 15 is so located as to extend from a midpoint on the top of the toe to a midpoint on the bottom, when worn, and is thus so located as to be conveniently positioned between the toes of the wearer.

The terry knit toe is softer and better wearing than the conventional toe. It is not necessary to brush the terry loops into individual fibers. In fact, it is preferable not to brush the terry loops since brushed terry loops have a tendency to felt or mat and become hard.

The formation of the terry toe according to the invention speeds up the operation of the knitting machine by eliminating the reciprocating movement necessary to form the conventional toe. The method also simplifies the knitting machine in that the use of terry mechanism with a continuously rotating machine does not require as complicated a set-up as terry mechanism with reciprocating heel and toe mechanism.

While certain novel features of the invention have been disclosed herein, and are pointed out in the annexed claims, it will be understood that various omissions, substitutions and changes may be made by those skilled in the art without departing from the spirit of the invention.

What is claimed is:

1. A seamless hose including a top; a leg portion and foot portion, said leg portion and said foot portion comprising tubular plain knit fabric whose courses extend entirely around the tube of the hose, said leg portion and foot portion having a heel pocket therebetween of plain knit fabric having courses extending part way around the tube of the hose, and a toe portion comprising tapered side flaps having curved cut edges, said side flaps comprising plain knit fabric having terry loops on the inside and whose courses extend continuously from edge to edge, a stitched seam connecting said curved cut edges, said seam comprising parallel welts formed by said edges projecting on the inside of the hose, an outer thread on the outside of the hose and passing through said welts, and an inner thread interengaged with said outer thread and binding the edges of said welts, said terry loops cushioning said seam, said seam extending from a midpoint on the top of the toe to a midpoint on the bottom of the toe in such position as to be adjustable between the toes of the wearer.

2. The method of making seamless hose which comprises plain knitting on a tubular knitting machine the leg portion to form a plurality of courses extending continuously around the tube, plain knitting a heel portion to form a plurality of variable length courses extending part way around the tube, plain knitting a foot portion and then a toe portion to form a plurality of

courses extending continuously around the tube, incorporating an additional yarn at the beginning of the toe portion to form terry loops on the inside of the tube, removing the hose from the knitting machine, turning the hose inside out, flattening the tubular toe portion, cutting said toe portion to form tapered toe flaps, abutting the edges of said flaps to form parallel welts and stitching and binding said welts to form a seam on the inside of the hose.

3. The method of making seamless hose which comprises plain knitting on a tubular knitting machine the leg portion to form a plurality of courses extending continuously around the tube, plain knitting a heel portion to form a plurality of variable length courses extending part way

around the tube, plain knitting a foot portion and then a toe portion to form a plurality of courses extending continuously around the tube, incorporating an additional yarn at the beginning of the toe portion to form terry loops on the inside of the tube, removing the hose from the knitting machine, turning the hose inside out, flattening the tubular toe portion, cutting both sides thereof to form tapered toe flaps, abutting the edges of said flaps to form parallel welts and connecting said abutting welts by an outer thread passing through said welts and an inner thread interengaging said outer thread to bind said welts and to form a seam on the inside of the hose.

ROBERT E. DAVIS.
